UNITED STATES PATENT OFFICE.

LEO WEISS AND ADOLPH WEISS, OF NEW YORK, N. Y., ASSIGNORS TO AUTOMAT PAPER BOX CO., INC., OF BROOKLYN, NEW YORK, A CORPORATION OF NEW YORK.

METHOD OF MAKING BOXES.

Application filed September 22, 1921. Serial No. 502,313.

To all whom it may concern:

Be it known that we, LEO WEISS, a citizen of the Republic of Czechoslovakia, and ADOLPH WEISS, a citizen of the United States, and both residents of the borough of Brooklyn, city of New York, in the county of Kings and State of New York, have jointly invented certain new and useful Improvements in a Method of Making Boxes, of which the following is a specification.

This invention relates to a method of making boxes. Its object includes the steps, by means of which a box, preferably of cardboard is made of a blank folded to form the bottom and neck of the box, and a frame preferably of cardboard, with suitable strips preferably of paper fastened to the neck and bottom of the box. The steps include the folding of one edge of one of said strips over an edge of the frame and the folding of the other edge on to the bottom of the box. The steps also include the fastening of the second strip with its main portion to the outer face of the neck of the box and with one of its edges turned over the edge of the neck and fastened to the inner faces of the latter.

The method includes the winding of the frame with its strip around the neck and the winding of another strip around the neck, while one end of the latter strip is free, to avoid any crease while the latter strip is fastened in place. The method includes steps to fasten together the frame and its strip with an adhesive, steps to fasten a strip to the neck with an adhesive and steps to fasten the frame to the neck with an adhesive.

Figs. 1 and 1^a represent a front elevation of a machine to carry out the steps of the method; Fig. 2 represents a section of Fig. 1^a on the line 2, 2; Fig. 3 shows a front elevation of some details; Fig. 4 indicates a front elevation of some details; Fig. 5 shows a side view and partial section of Fig. 4 on the line 5, 5; Fig. 6 represents a section of Fig. 1 on the broken line 6, 6, and on the line 6^a, 6^a; Fig. 7 shows a section of Fig. 1^a on the line 7, 7; Fig. 8 represents an enlarged fragmentary top plan view of Fig. 1; Fig. 9 shows a section of Fig. 1^a on the line 9, 9; Fig. 10 shows an enlarged fragmentary portion of Figs. 1 and 1^a with some of the parts in a changed position; Fig. 11 shows an enlarged fragmentary portion of

Fig. 10; Fig. 12 represents a side view of Fig. 11 with sections of the material operated upon; Fig. 13 indicates a top plan view of the box partly constructed; Fig. 14 shows a section of Fig. 13 on the line 14, 14; Fig. 15 indicates a plan view of the blank for forming the bottom and neck of the box; Fig. 16 shows a side elevation of the finished box and Fig. 17 indicates a bottom plan view of Fig. 16.

The machine exemplifying the steps of the method comprises a table with the platform 20 supported on legs 21. A frame 22 and a head 23 extend up from the platform 20. In the latter is supported the barrel 24 which intermittently rotates with the tubular shaft 25. A rotating shaft 26 extends across the machine and has fastened thereto a segmental gear 27 which meshes with a gear 28 carried on the tubular shaft 25. The tubular shaft 25 can slide through the gear 28. By means of the said segmental gear, the gear 28 with its tubular shaft 25 have imparted thereto intermittent rotation.

A hollow forming block 35 is fastened to one end of the tubular shaft 25 and at the other end of the said shaft is secured a sleeve 36. An annular flange 37 is fastened to the sleeve 36. A stationary disc 38 is located within the sleeve 36 and bears between the inner face of the flange 37 and the adjacent end of the shaft 25. Packing 39 bears between the disc 38 and the sleeve 36 to prevent leakage. A reciprocating valve stem 40 is contained in the shaft 25 and has one end fastened to the knockout plate 41 which functions also as a valve with the outer wall of the forming block 35. The plate 41 in this instance is indicated as rectangular in contour but may be made circular. The plate 41 has openings 42 formed therein and openings 43 are also formed in the four walls of said forming block 35.

A stationary guide bracket 47 supports the valve stem 40. Piping 48 extends through the disc 38 and the bracket 47. A three way cock is indicated at 49 and a hose 50 connects the piping 48 and the said three-way cock. A cam 51 is fastened to the shaft 26. A link 52 is actuated at one end by the cam 51 and the other end of said link 52 is pinned to the arm 53 of the three way cock 49.

A stationary grooved cam 55 with the cam

groove 56 extends up from the platform 20. A disc 57 is fastened to the shaft 26 and a plurality of folders 60, 61, 62, 63 and 64 are fastened to the disc 57 and have journaled at their inner ends the rollers 65 that engage the cam groove 56.

A frame 69 with the forming die 70 extends from the barrel 24. Guides 71 extend from the die 70. A gripping finger 72 is pivoted to the die 70 and has an arm 73 with a roller 74. A spring 75 has one end fastened to barrel 24 and its other end is fastened to the arm 73 as indicated in Fig. 5. A tubular cam 76 with the notch 77 oscillates on the barrel 24. By means of the movements of the cam 76, the finger 72 is swung adjacent to the forming block 35 at the proper time, and when the roller 74 engages the notch 77 the spring 75 separates 20 the finger 72 from said forming block.

At the upper portion of the head 23 is located a magazine table 83 which has formed therewith the guides 84. Side walls 85 are located above the table 83. A sliding carriage is indicated with the front wall 86 and the rear wall 87. Tie rods 88 connect the walls 86 and 87. The lower ends of the walls 86 and 87 bear on the guides 84. Pulleys 89 are journaled over the table 25 83 and cords 90 have one end each fastened to the wall 87, pass over the pulleys 89 and extend through openings 91 formed in the table 83. Weights not shown are attached to the other ends of the said cords.

35 A bracket 95 abuts against the front end of the table 83 and has formed therewith the bearing strips 96. Guides 97 are fastened to the front face of the bracket 95. A cross head 98 is engaged in the guides 97. 40 Journal bearings 99 and 100 are located above the guides 97 and support a shaft 101. An arm 102 has one end fastened to the shaft 101 and to its swinging end is pinned one end of the link 103. The other end of 45 the link 103 is pinned to the crosshead 98. An oscillating arm 104 has one end fastened to the shaft 101. By means of the oscillations of the arm 104 and the interposed elements the cross head 98 is reciprocated. A 50 pair of rotating rollers 105 are journaled to the bracket 95 below the cross head 98.

A bracket 106 with the openings 107 and 55 108 extends up from the platform 20. A bracket 110 extends from the front face of the bracket 106. A reciprocating slide bar 111 is supported by the bracket 110 and carries the presser plate 112. An arm 114 is pivoted to the support 106 and has one end pinned to the slide bar 111. To the 60 other end of the arm 114 is pinned a reciprocated link 115. By means of the reciprocations of the link 115 and the interposed elements the slide bar 111 is reciprocated.

65 A reciprocating slide 116 is slidably sup-

ported in the bracket 106 and supports a die 117 having a rectangular opening 118. Guides 119 extend up from the platform 20 and support the reciprocating slide bar 120 to which latter is secured a cup shaped 70 head 121. A second reciprocating slide bar 122 is guided in the bar 120 and has fastened thereto the plate 123. Folding wings 124 are pivoted to the four sides of the head 121. A sleeve 125 with the flange 126 encircles the slide bar 122 and a spring 127 encircles the sleeve 125 and bears between the bottom of the head 121 and the flange 126. Stationary strippers 128 bear against the side walls of the head 121. 80

A disc 129 having a cam groove is fastened to the shaft 26. An arm 130 is pivoted in a journal bracket 131 extending from the platform 20. A roller 132 is pivoted on the arm 130 and engages the cam 85 groove of the disc 129. A journal bracket 133 extends from the platform 20 and has pivoted thereto an arm 134. A link 135 connects the arms 130 and 134 and a link 135^a has one end thereof pinned to the slide 90 116 and its other end is pinned to the arm 134. By means of the rotations of the shaft 26 and the interposed elements the slide 116 is reciprocated at the proper times.

A guide bracket 136 extends up from the platform 20 and slidably supports a slide bracket 137. A supporting table 138 is carried on the bracket 137. An oscillating guide bracket 139 is pivoted on the slide bracket 137. The bracket 139 is provided 100 with the roof plate 140 which connects with the inclined guide plate 141.

A hinged guide plate 142 is pivoted on the guide bracket 139. The plate 142 has formed on its upper face the guide bars 143 and on its lower face the guide bars 143^a. An arm 144 extends from the bracket 139 and has pivoted thereto the roller 145. A horizontal guide 146 with the upper guide plate 147 is supported to the rear 110 of the bracket 136 for the roller 145. A spring 148 bears between the forward end of the bracket 139 and the bracket 137. An oscillating shaft 149 is journaled in brackets 150 fastened to the slide bracket 137. 115 Gripping fingers 151 and 151^a are secured to the shaft 149. A glue pot 152 with the roller 153 is supported on the vertical bar 154. An oscillating lever 155 is pinned to the bar 154 and thereby the said glue pot 120 with its roller is raised from its normal position at the proper times. A folder 199 is attached to the frame 22.

A slide 160 (Fig. 1^a) having formed therewith the guide table 161 is slidably located in guides 162 extending from the frame 22. A spring 163 bears up against the bottom end of the slide 160. A swinging lever 164 bears upon the table 161. 125

A bracket 170 extends from the head 23. 130

- An arm with the members 171 and 172 and roller 173 is pivoted to the bracket 170. A cam 175 extends from the die 70 and contacts with the roller 173.
- 5 A guide bracket 180 slidably supports the slide bars 181 with the upper clamping finger 184. A third slide bar with the lower clamping finger 182 slides between the slide bars 181.
- 10 A guide bracket 190 supports the slide bar 191 which supports the upper shears 192. A similar guide bracket, with a slide bar, is provided for the lower shears 197.
- 15 Pairs of guides 200 and 201 are secured to the frame 22 of the machine. The guide plate 205 with guide bars 206 and 207 is secured in place over the said pairs of guides. A cutter is indicated with the stationary member 210 which is supported on the frame 22, and the swinging knife blade 211. The latter is fastened to the swinging arm 212 which is pivoted above the frame 22. A disc 213 having a cam groove is fastened to the shaft 26. A journal bracket 215 is fastened to the platform 20 and has pivoted therein the bell crank with the arms 216 and 217. A roller 218 is journaled in the end of the arm 217 and engages the cam groove of the disc 213. A journal bracket 223 is supported on the platform 20 and has pivoted therein the bell crank with the arms 224 and 225. A link 226 connects the arms 224 and 216. A link 227 connects the arms 212 and 225. By means of the rotations of the disc 213 and the interposed elements the knife blade 211 is given a swinging movement at the proper times.
- 20 A bracket 230 is fastened to the pairs of guides 200 and 201 and has connected thereto a stop plate 232 with the lateral extensions 233. A presser foot 235 with gripping pins 235^a is shown with the vertical member 236. Vertical extensions 237 and 238 extend from the vertical member 236 and a cross piece 239 connects the extensions 237. The vertical member 236 is guided in the stop plate 232. Guide plates 240 are fastened to the bracket 230. A horizontal slide plate 241 reciprocates upon the bracket 230 under the guide plates 240.
- 25 A bracket 243 is fastened to the front of the frame 22 and supports a guide plate 244 with the curved end 245.
- 30 A horizontal plate 250 with the guide flanges 251 is supported on the frame 22. Journal brackets 252 and 253 extend up from the plate 250. A shaft 255 is journaled in the brackets 252 and 253. An arm 256 has one end fastened to the shaft 255 and its other end is pinned to a reciprocating lever 258. A sleeve 260 is supported on the shaft 255 and has extending therefrom the arm 261 which is pinned to a reciprocating lever 262. An arm 263 with a cam groove extends from the sleeve 260.
- 35 A pin 265 (see Figs. 6 and 8) is supported in brackets extending from the slide plate 241. The said pin extends through the cam groove of the arm 263. An arm 266 is fastened to the shaft 255 and extends under the cross piece 239. Rotating rollers 268 are journaled above the plate 250. A guide bracket 270 with the roller 270^a extends from the platform 20 and a guide roller 271 is journaled in the guides 200.
- 40 A glue pot 275 with the glue distributing disc 276, the guide wheel 277 and the reel 278 are located adjacent to the platform and to the left thereof. In the drawing the glue pot 275 is shown below the platform 20 to be enabled to show it on the same sheet of drawing. A second glue pot 285 with the glue distributing disc 286, the guide wheel 287 and the reel 288 are located under the platform 20.
- 45 To carry out the steps of the method to make the box a strip of material A, of paper in this instance, is unwound from the reel 288 and, coated on its face *a*, by means of the disc 286 of the glue pot and located upon the guide plate 244 with its end about under the right hand end of the stationary member 210 of the cutter.
- 50 Next a piece of card board B preferably scored at *b* is located upon the horizontal plate 250, and brought under the rotating rollers 268, which moves its edge against the stop plate 232 and its extensions 233, the presser foot 235 being at this time in its raised position. This locates a requisite amount of the card board B upon the stationary member 210 of the cutter. The presser foot 235 is now brought down upon the card board B with the downward swing of the arm 266, caused by the oscillation of the shaft 255. This causes the gripping pins 235^a to grip the card board and the latter is securely positioned upon the member 210. The knife blade 211 now descends and cuts a strip from the card board B to produce a frame C. The presser foot 235 together with the stop plate 232 now moves forwardly by reason of the forward movement of the slide plate 241. The plate 241 slides forward by reason of the coaction of the arm 263 and the pin 265. With the forward movement of the presser foot 235, the gripping fingers 235^a force the frame C to move with the said presser foot. The latter now descends and locates the frame C upon the side *a* of the strip A. The presser foot 235 remains in its lowered position until the three gripping fingers 235^a on the left hand end of the oscillating shaft 149 bear down on frame C, after which the presser foot 235 rises and together with the stop plate 232 both return to their original positions.
- 55 The slide bracket 137 now moves in the direction of the arrow X and carries the

forward end of the frame C in line with the cutting edges of the lower shears 197. While the bracket 137 moves the strip A it is folded over an edge of frame C by means 5 of the folder 199, as indicated at a^2 (Figs. 13 and 14).

At this time a strip E of paper has been 10 unwound from the reel 278, coated on the side e with an adhesive from the glue pot 275 and located upon the guide plate 205 with its end in line with the cutting edges 15 of the upper shears 192 and advanced horizontally a short distance beyond the cutting edges of the lower shears 197. The clamping fingers 182 and 184 now descend and 20 locate the end of the strip E upon the frame C and the already folded over portion a^2 of the strip A. The gripping finger 151^a now bears down on the frame C and the strips 25 A and E. The three gripping fingers 151 on the left hand end of the shaft 149 grip a second frame C¹ with its strip A while the remaining gripping fingers 151 grip the frame C with its strip A. The clamping 30 fingers 182 and 184 now rise in an open position and permit the strip E to move between them. The slide bracket 137 now moves forward to the position shown in Fig. 9 and carries forward the frames C and C¹ 35 with their strips A in conjunction with the strip E. The first frame C with its strip A and the forward end of the strip E are located below the folding block 35. The lever 164 now rises which permits the guide bracket 139 to swing up under the tension 40 of the spring 148, which causes the swinging end of the plate 139^a of the bracket 139 to force the frame C with the strips A and E against the neck of the box to be described 45 located on the forming block 35. At the same time the gripping finger 72 which can swing through a notch in the plate 139^a bears up against the frame C and the strips A and E to hold them in place. Just before 50 the forming block 35 turns, the clamping fingers 182 and 184 clamp the strip E. Both shears 192 and 197 now operate and the upper shears 192 sever the strip E while the lower shears sever the strip A between the adjacent ends of the two frames C and C¹.

The shears 192 are somewhat advanced 55 horizontally beyond the shears 197 to allow a small length of the strip to form an overlap a^2 when finally located in place on the neck of the box that is being formed.

Blanks H for the combined neck and bottom are located on the guides 84 and by 60 means of the sliding carriage having the walls 86 and 87 are pressed against the cross head 98. The latter forces the blanks H one at a time into the guides 71 of the rotating frame 69, when the forming block 65 is in its first position indicated at 1, Fig. 2. The forming block 35 now moves horizon-

tally forward and forces the blank H through the opening of the die 70, and by means of which the sides of the blank are turned at right angles to its body to form the neck H¹ of the box. While in this position suction is produced in the forming block 35 by means of an air pump coating with the cock 49 and thereby the blank H temporarily adheres to the end and sides of said block 35. The forming block with its blank is next moved to the second position indicated at 2, Fig. 2.

The frame C and the strips A and E are now brought into contact with the neck H¹ of the box and the forming block 35 begins to turn, and simultaneously the folders 60 to 64 one after the other fold the extending portion of the strip A on the bottom H² of the partially formed box. Each of the folders 60 to 64 performs its function when 80 opposite one of the lower sides of the forming block 35. The forming block 35 with its partially finished box is now moved to its third position indicated at 3 (Fig. 2) and is located in the die 117 of the slide 116. 85 The plug of the cock 49 now turns to release the suction. The forming block 35 next returns to the first position, and at the same time the knockout plate 41 retains the box in the die 117 until the forming 90 block 35 is out of contact with the box and moves back into the forming block 35. The slide 116 now moves to the right to locate the partially formed box axially in line with the cup shaped head 121. The head 121 with its folding wings 124 advance toward the box. The wings 124 close in and bend the extending portion e' of the strip E around the edges of the neck H² of the box. The head 121 advances the wings 124 and 95 forces the extending portions of the strip E against the inner faces of the neck H². The plate 112 now advances and bears against the bottom of the box. At the same time the head 121 with the box thereon moves out of the die 117. When the box is 100 clear of said die the presser plate 112 returns to its original position. As the head 121 recedes the strippers 128 detach the box 105 from the head 121 and it is ready for use.

It will be noted that the roller 153 only coats the frame C with an adhesive while it is moving. It will also be noted that when the frame C with the strip A is under the guide plate 142 the latter at its swinging end bears on the frame C with its strip A without coming in contact with the adhesive on the frame. The guides 143 at the same time gauge the strip E to locate the parts in proper position just before contacting with the neck H² on the folding block 35 of the partially formed box. The arm 172 bears down on the strip E at the proper time with the coaction of the cam 175 and the roller 173. It will be also noted that as the 110

frame C is wound around the neck that the strip E will follow the neck as it is wound, avoiding creases as it is located in position.

5 The ends of the frame C when in position around the neck H' form a butt joint and the overlap α^2 joins the said ends.

Having described our invention what we desire to secure by Letters Patent and claim 10 is:—

1. The method of making a box consisting in folding a blank to form the bottom and neck thereof and subjecting the bottom and neck to suction to maintain them in proper related position, winding a frame with strips around said neck and attaching them thereto.

2. The method of making a box consisting in folding a blank to form a bottom 20 and neck therefor, rotating said bottom and neck and fastening a frame with strips to said neck and bottom during said rotation.

3. The method of making a box consisting in folding a blank to form a bottom 25 and neck therefor, fastening a strip to the outer face of a frame for the box with its edges extending beyond the frame, bending said strip over one of the edges of the frame, fastening the bent over portion of the strip

30 to the other face of the frame, securing a second strip to the neck with a portion of said strip extending beyond the top edge of the neck, folding the edge of the second strip over the edge of the neck and fastening it to the inner face thereof, fastening the frame to the neck, folding the extending portion of its strip to the bottom of the box and fastening it thereto.

4. The method of making a box consisting 40 in folding a blank to form a bottom and neck therefor, fastening a strip to the outer face of a frame, bending said strip over one of the edges of the frame fastening the bent over portion to the other face of the

45 frame, securing a strip to the neck while the latter is turning with a portion of said strip extending beyond the top edge of the neck, folding said extended portion of the latter strip over the edge of the neck and fastening it to the inner face thereof while at rest, fastening the frame to the neck while the latter is turning and fastening the strip of the frame to the bottom of the box while the latter is turning.

55 5. The method of making a box consisting in folding a blank to form a bottom and neck therefor, fastening a strip to a frame for the box, fastening one end of a second strip to the frame, turning the bottom and neck of the box, fastening the frame with its strip to the neck while the latter is turning, the second strip following the frame and fastened to the neck during the rotations of the latter.

65 6. The method of making a box consisting

in folding a blank to form a bottom of the main portion of the blank and a neck of the folded over portions, cutting card board into strips to form frames for the box, locating and fastening the frames upon a 70 strip of paper having an adhesive thereon with the edges of the strip of paper extending beyond the edges of the frame, folding one edge of the strip of paper over one edge of the frame and fastening the 75 folded over portion to the other side of the frame, locating and fastening a second strip of paper upon the turned over portion of the first strip of paper and upon said frame, the second strip extending beyond the front 80 end of the frame and comprising an overlap, clamping an end of the frame with strips of paper to a wall of the neck, turning the neck, winding the frame with its strips around the neck, folding the extending edge 85 of the first strip on to the bottom of the box while turning and fastening it thereto, folding the extended edge of the second strip over the edges of the neck and fastening it to the inner faces of the neck. 90

7. The method of making a box consisting in folding a blank to form the bottom and neck thereof, maintaining the bottom and neck in proper related position, locating and fastening with an adhesive a strip of paper to one side of a frame and folding an edge of the strip over an edge of the said frame and fastening the bent over portion of the strip to the other side of the frame, fastening with an adhesive one end of a second strip of paper to the frame and its strip, fastening the frame with its strip and the second strip to a wall of the neck and turning the neck, to simultaneously wind the frame with its strip and the second strip 100 around the neck, the second strip maintained spaced from the frame and the first strip until they are all simultaneously fastened to the neck of the box.

8. The method of making a box consisting in folding a blank to form a bottom and neck for the box, locating and fastening the end of a strip to a frame that has attached thereto a strip, fastening the first strip and the frame with its strip to the neck, turning the neck and thereby winding the first strip and the frame with its strip around the said neck and maintaining the first strip free and separated from the frame and its strip until the said three elements come together on the neck. 110

9. The method of making a box consisting in folding a blank to form a bottom and neck for the box, locating and fastening the end of a strip on one end of a 125 frame having a strip attached thereto, the strip of the frame at one side extending beyond one side thereof, turning the neck and bottom, to locate and fasten the first strip and the frame with its strip to the 130

sides of the neck as it turns, and folding over the extended portion of the strip of the frame to the bottom of the box as the frame is located on the walls of the neck.

- 5 10. The method of making a box consisting in folding a blank to form a bottom and neck for the box, coating the top face of a strip with an adhesive, a frame with a strip attached thereto, locating an adhesive on the top face of the frame, fastening one end of the first strip to the end of the top face of the frame with its strip, fastening the end of the first strip with the end of the frame and its strip to the outer face of one of the walls of the neck, turning the neck and thereby winding both strips and the frame around the outer faces of the walls of the neck, guiding the first strip relatively to the frame and its strip 15 and maintaining both strips and the frame, in proper alignment with the walls of the neck.

11. The method of making a box consisting in folding a blank to form a bottom and neck for the box, securing a strip to the lower side of a frame, bending an edge of the strip over an edge of the frame and fastening it thereto by an adhesive on the face of the frame having the bent over portion of the strip, locating the end of a second strip on the frame and the bent over portion of its strip, the upper face of the second strip having an adhesive, pressing a portion of the second strip to the frame and its strip, and locating the frame and the two strips around the said neck.

- 20 12. The method of making a box consisting in folding a blank to form a bottom and neck for the box, locating an adhesive on the top face of a strip, fastening a number of frames on the top face of the strip, moving forward the strip with a number of the frames thereon, bending an edge of the strip over the frames and fastening the bent over portion to the top face thereof, locating and fastening an end of a second strip to the top face of one of the frames, moving for-

wardly the first strip with its frames and the second strip, fastening the forward ends of one of the frames with its strip and second strip to the lower outside face of a wall of the neck, severing both strips, turning the neck and thereby winding one of the frames with the strips around the neck and folding a portion of the first strip to the bottom of the box.

50 13. In the method of making a box, locating a number of frames on a strip having an adhesive thereon, moving the strip with the frames forwardly the length of one frame, stopping the movement, locating another frame on a portion of the strip that has been advanced, severing the strip at the ends of the frames and winding each frame with its portion of the strip around 55 the neck of the box.

14. In the method of making a box, locating a number of frames one after the other on a strip, advancing the strip with its frames and stopping the movement and thereby locating a portion of the strip not having any frame thereon in position to locate and secure a frame on said portion adjacent to the last frame previously fastened to the strip, severing the strip at the 70 ends of the frames and winding each frame with its portion of the strip around the neck of the box.

75 15. In the method of making a box, locating and fastening a strip to the outer face of a frame, folding an edge of the strip over the frame and fastening it to the inner face thereof, locating an end of a second strip to the inner face of the frame simultaneously advancing the frame and 80 said strips and locating said elements around and fastening them to a partially formed box.

85 Signed at the borough of Brooklyn, city of New York, in the county of Kings and State of New York, this 13th day of September, A. D. 1921.
